UNITED STATES PATENT OFFICE.

CARLYLE C. PRINDLE, OF DOUGLASTON, NEW YORK.

VANITY BOX.

Application filed February 12, 1923. Serial No. 618,479.

To all whom it may concern:

Be it known that I, CARLYLE C. PRINDLE, a citizen of the United States, and a resident of Douglaston, Long Island, in the county of Queens and State of New York, have invented certain new and useful Improvements in a Vanity Box, of which the following is a full, clear, and exact description.

Among the principal objects which the present invention has in view are: to provide an article of the character mentioned with means for carrying loose face powder; to prevent the escape or leaking of the powder from the container; to promote neatness within the box by preventing the powder over-riding the edges of the well provided therefor; to facilitate re-loading or recharging of the box with powder; to provide means for assisting in the removal of the pad; and to secure neatness and elegance of construction.

Drawings.

Figure 1 is a perspective view of a vanity box constructed and arranged in accordance with the present invention, the lid of the box being open and the powder puff partially removed from the box.

Figure 2 is a section taken diagonally of the box and as on the line 2—2 in Fig. 1, the lid of the box being closed and the pad being indicated therein by dotted lines.

Figure 3 is a longitudinal section of the box.

Figure 4 is a perspective view of a cover for the powder-holding compartment of the box showing a modified form of the invention.

Figure 5 is a cross section of the same, the section being taken on the line 5—5 in Figure 4.

Description.

Heretofore, vanity boxes have been provided with face powder pressed to form cakes of somewhat solid character from which the powder has been wiped by means of a suitable pad to be thereafter put upon the face of the one using the box. Various disadvantages have arisen in the use of these compacts, one disadvantage being that the certain desired face powders have not been put up in this form. Another disadvantage has been that manufacturers of certain lines of face powders have so shaped their com-

pacts and containers therefor as to compel the use of the product of the proprietary manufacturer.

The advantages incident to the use of loose powder are well known, the single disadvantage being that where a box that is to be carried with the person is employed, constant danger of the powder being emptied from the box or of spilling while being used. This in the present invention is avoided.

Referring to the drawings it will be seen that the numeral 10 indicates a box body. The body 10 in conjunction with an open-centered top 11 forms a chamber for holding the loose powder 12. As shown, the top 11 is preferably held within a groove formed by an outwardly projecting ridge 13 formed in an insert, the upper portion of which forms a guide flange 14 for the cover 15.

The top 11 is slightly depressed toward the center thereof. The open center is partially surrounded by a dropped flange 16, the lower edge of which is inturned to form a support for a pan. The flanges 16 are extended from the longer sides of the opening in the top 11, the said flanges being omitted at the oblique corners 18. Omitting the flanges in this manner as shown in Fig. 2 of the drawings serves to provide narrow slit openings above the pan 17 at all of the said oblique corners. In service the powder 12 from the holding chamber of the box 10, is shaken through and seeps through to spread over the pan 17.

The pan 17 as is shown best in Figures 2 and 3 is depressed toward the center, in this manner facilitating the movement of the powder over the pan towards the said center, or away from the periphery of the opening of the top 11. In this manner any lodgment of the powder on the top 11 is avoided.

To prevent packing of the powder at the center of the pan 17 I have provided the knob 19. The knob 19 also serves to lift the bow 20 which serves as a handle for the powder puff 21. By this means the center of the powder puff is prevented from sinking to avoid the finger and the thumb of the user when seeking to lift the puff from the box.

The cover 15 is provided with the usual mirror 22 and is preferably attached to the box body 10 by a hinge 23.

The pans 17 and 24 have a lifting clip 25 by means of which the pan is lifted from its service position. Both styles of pans

extend into the depressed opening of the top 11 and rest firmly on the flanges 16. The spring of the dropped portions having the flange 16 serve to lock or hold the pans 17 and 24 firmly in service position. When it is desired to remove the said pans, the finger nail or some suitable device is extended below the clip 25 and pried upward so it will be found that the pans are easily removed.

10 It will be found that when the pans have been removed that the holding compartment of the box 10 can be easily charged with powder.

15 The modification shown in the pan 24 as seen in Figures 4 and 5 is that the knob 19 has been omitted therein.

It is obvious that in service when the cover 15 is closed the powder puff 21 is pressed firmly upon the top 11 and the powder which 20 seeps through the openings under the edges 18 to the pan 17 is held from drifting from the said pan to the top 11, while the center of the pad is fully supplied with the said powder. In this manner the box resents at 25 all times a neat and clean appearance.

Claims.

1. A vanity box comprising a powder holding compartment; an open-centered top 30 therefor; a covering pan removably secured in service on said top for closing the center thereof; means communicating with the interior of said compartment for delivering a small quantity of powder from said compartment to the upper side of said pan; and a closure cover for said box adapted when closed for pressing a manipulator for said powder close upon said pan for limiting the delivery of said powder from said compartment to said pan.

2. A vanity box comprising a powder holding compartment; a top therefor having a depressed and open center for loading said compartment; a covering pan re-

45 movably secured to said top within the depressed portion thereof, portions of said pan being below the edge of said top to form in conjunction therewith delivery slits communicating between said compartment and the upper side of said pan; and a closure 50 cover for said box adapted when closed for pressing a manipulator for said powder close upon said pan for limiting the delivery of said powder from said compartment to said pan.

3. A vanity box comprising a powder holding compartment; an open-centered top having dropped flanges partially surrounding said opening; a covering pan removably and firmly supported within the opening of 60 said top, said pan being arranged to provide limited openings under said top for delivering of the powder in said compartment to the upper side of said pan; a closure cover for said box adapted when closed for 65 pressing a manipulator for said powder upon said pan for limiting the delivery of said powder from said compartment to said pan; and means for elevating the center of 70 said manipulator.

4. A vanity box comprising a powder holding compartment; an open-centered top having dropped flanges partially surrounding said opening; a covering pan removably and firmly supported within the opening of 75 said top, said pan being arranged to provide limited openings under said top for delivering of the powder in said compartment to the upper side of said pan; a closure cover for said box adapted when closed for pressing a manipulator for said powder upon 80 said pan for limiting the delivery of said powder from said compartment to said pan; and means for elevating the center of said manipulator, said means embodying a raised 85 center of said pan.

CARLYLE C. PRINDLE.
